TRUCK CAB

Dean Hobbensiefken, Rte. 1, P.O. Box 241,
Lyons, Oreg.

Filed Nov. 23, 1971, Ser. No. 201,625

Term of patent 14 years

Int. Cl. D12—08

U.S. Cl. D14—3

FIG. 1

FIG. 2

FIG. 3

FIG. 4

FIG. 1 is a perspective view of a truck cab showing my new design;

FIG. 2 is an enlarged front elevation thereof;

FIG. 3 is a side elevation thereof, the opposite side being a mirror image, and

FIG. 4 is a rear elevation thereof.

I claim:

The ornamental design for a truck cab, as shown and described.
